UNITED STATES PATENT OFFICE.

FELIX BENEDICT HERZOG, OF NEW YORK, N. Y.

ELECTRIC SIGNALING APPARATUS.

SPECIFICATION forming part of Letters Patent No. 696,140, dated March 25, 1902.

Application filed September 29, 1884. Serial No. 144,184. (No model.)

To all whom it may concern:

Be it known that I, FELIX BENEDICT HERZOG, a citizen of the United States, residing at New York, in the county and State of New York, have invented a new and useful Improvement in Electric Signaling Apparatus, of which the following is a specification.

In Letters Patent No. 289,834, issued to me December 11, 1883, I have described an automatic signaling apparatus applicable to many different uses, such as telephone-exchange service, district-telegraph and private circuits, hotel-annunciators, &c., the main feature of which is that the apparatus may be properly set by a person desiring to signal to a distant point in such a manner that the desired signal is not sent at the moment of setting the instrument, (as is the case in instruments of the class known as "transmitters,") but the apparatus retains the signal as set until this is released directly or indirectly from some point beyond by the person who is to receive the signal when he is ready for it. My present invention consists of several modifications and additions thereto.

It consists, first, in combining a number of such instruments upon the same circuit in such manner and in so constructing them that if one is set all the others beyond it are cut out of circuit either automatically by the act of setting or independently of that act, so that no instrument can be released so as to transmit its signal until after the release of all those that may have been set that are nearer the station; secondly, that when the instrument has been so released or unset and has finished the transmission of its own signal it automatically sets in circuit the next instrument beyond, so that if this is set it in its turn releases its signal, and so on; thirdly, it consists in an arrangement of circuits and instruments whereby the act of setting any one instrument in the circuit automatically signals to the receiver the fact that an instrument on the circuit has been set; fourthly, in that the act of setting the instrument also changes the current in circuit, so that the signal will not be released when set, as would otherwise be the case, but will remain set until this change is effected by the receiving operator, and thus the signal set is not released until this operator is at leisure to attend to

it; fifthly, it consists in such further improvements in this signaling apparatus as are hereinafter described.

I shall for convenience of description call the form of signal I have shown in my Patent No. 289,834 in this and in contemporaneous applications a "latent" signal, for the reason that when the signal is set it remains inoperative until released from another station.

In the accompanying drawings, Figure 1 represents a series of my latent signals arranged upon the same circuit and constructed according to my invention. Fig. 2 is a detail of the latent signal. Fig. 3 is a front view of my latent signal, showing its internal construction. Fig. 4 illustrates my invention as applied to a "district-telegraph system," showing a series of district-telegraph instruments or boxes on the same circuit constructed and connected according to my invention. Fig. 5 represents the front of a latent signal provided with three separate dials and capable of sending several separate signals successively. Fig. 6 shows modification in the forms of character-disks for transmitting the proper signals under certain conditions.

In Fig. 1, D', D, D, and D" represent a series of latent-signal instruments placed in the same circuit in series, as shown. As all are constructed in the same manner, it is only necessary to describe the instrument D', which is substantially the same in construction as the instrument described in the patent already referred to and clearly shown in Fig. 3. It consists of a clockwork-transmitter J, provided with a transmitting-disk B, for sending the signal in the usual manner, and an electromagnet C, the armature of which controls the escapement of the clockwork, so that the transmitter or latent-signal instrument may be released by sending a current through the circuit. Referring again to Fig. 1, this instrument is provided with two hands on the outside of the box, one of which, M, is attached to the spindle carrying the character-disk and the other of which, N, is mounted on the front of the box, so that it may be set independently in any desired position, so as to limit the revolution of the other hand, and thus determine the signal transmitted, exactly as described in my previous patent referred to. Upon the independent hand N is

mounted a flat spring O, rigidly screwed to a projection n, attached to but insulated from the metal hand itself. This projection n passes through the hand, as is clearly seen in Fig. 2, and terminates in a spring n', which travels over the face of a metal arc P, making constant electrical connection therewith. The outer end also of the hand N carries a projection s, which likewise ends in a brush bearing on the second metal arc S, as shown. In the present position of the hands the spring O is pressed in contact with the projection s, so as to connect the arc P with the arc S; but when the hand M in unwinding comes up to the hand N a pin m, projecting below this hand, comes against the spring O and as the hand continues turning carries it over from the contact-point s to the contact-point T, carried by the hand N, the consequence being that the spring O breaks connection with the arc S and makes connection with the metal hand N. The circuits in the instrument are arranged as follows: Entering the instrument at the binding-post Z, the circuit leads to the arc P, thence through the spring O to the arc S, thence to the contact-spring H and character-disk B, through the metal spindle L to the electromagnet C, and thence through the binding-post X to the ground or return circuit, whatever that may be. If the instrument is unset, the spring O will be over in contact with the point T, from which the circuit leads, through the metal hand itself, (which is mounted on the front of the box and is insulated from the spindle L,) to the binding-post W, whence the circuit leads, through the line-wire, to the next instrument D, as clearly shown in the drawings. It will now be understood that when all the instruments in the circuit are unset the circuit leads through them all in series, and it can be either a normally energized or unenergized circuit, as desired. When any instrument is set, all those beyond are automatically cut off, the circuit is grounded (or closed through a return-wire, as the case may be) through the transmitter and releasing-electromagnet, and therefore when a current is sent over the circuit to release the signaling instrument it will only release the one that is nearest to the receiving operator and will not affect the others until this instrument has ceased sounding its signal, when the hand M will carry over the spring O into contact with point T, thereby connecting in circuit the next instrument, which if it has also been set will then be released and will transmit its signal, after which it will connect in the next instrument, and so on. In order to separately distinguish the signals sent in by two or more successive instruments, there should be an interval between them, which should be recognizably longer than that between two signals. This is secured by arranging the contact-points s and T so that the spring O breaks connection with the one a considerable space of time before making connection with the other. It

is also necessary if only one signal or set of signals is received when the circuit is "tested" that means be provided whereby the operator can know which station has sent the signal. This I do by giving each station an arbitrary signal, such as is usual in district-telegraph boxes, in addition to the variable automatic signal to be transmitted. At the receiving-station where the signal is received there are placed in circuit an annunciator A', a switch B', and in branch 1 a battery B'', and in a branch circuit 2 a sounder or recording instrument C' and a battery B''', as shown. If the apparatus I have described be employed in a telephone-exchange system or in any case where separate magneto calls or other means are used for calling up the central office independently of any generator at such office, then the annunciator A' would be normally grounded and would be arranged to drop when such call was made, thus indicating this fact to the central operator. The latter thereupon or as soon as at leisure switches in the battery and receiving instrument C', whereupon if a signal be set upon some instrument upon the line the current from this battery instantly releases the instrument nearest the office that has been set, and the incoming signal is then read or recorded on the receiving instrument C'. In certain applications of my invention it is necessary to provide means whereby a station can signal to the end of the line without releasing a latent-signal transmitter which may be set at some intermediate station. I make such means the subject of another application, Case No. 67, Serial No. 318,181, filed July 20, 1889, Figs. 10, 11, and 13. Such necessity arises, for instance, in "combination" telephone-exchange circuits where the last subscriber on a line may desire to call up the central office without disturbing the signal of the other subscribers and without ringing their bells. If no calling apparatus be employed at the stations which is independent of the central generator, and if the circuit be a normally open one, then, if desired, according to my invention the mere act of setting any instrument closes the circuit at that instrument, and so if at the central station a battery B'' be kept in circuit the fact that an instrument has thus been set will then be shown by proper means, such as the annunciator A', which of course is constructed to operate upon closing the circuit. If the circuit be normally closed with this small battery on the line, (which may be placed in circuit between the key B' and the ground,) then the setting of any instrument will break the circuit momentarily, (while the spring O is moving from one contact-point to the other,) and this fact can readily be perceived at the central office.

The fourth instrument D'' in Fig. 1 I have shown double, which admits of more signals and, consequently, information being given from one office; but each operates independently and they transmit their signals suc-

sively in exactly the same manner as the separate instruments shown at different stations.

In Fig. 4, which represents my invention as applied to a "district-telegraph" circuit, D'', 5 D, D, and D' represent separate call-boxes constructed according to my invention and arranged on the same circuit as before. Each instrument consists of the clockwork signal-transmitter now in common use for district call-boxes, as shown, provided with the signal-disk B, the hand M for setting the instrument, the escapement G, &c. In addition to this well-known mechanism I arrange an electromagnet C, whose armature is carried by a bent lever E, from which projects a finger F, which is normally held by gravity in the way of the pendulum G and locks the escapement, but allows the pendulum to vibrate when the lever is rocked by the electromagnet C. The upper end of this lever E ends in a wedge-pointed elbow e, the edge of which bears upon the periphery of the metal sector A, screwed to the spindle L. I is an insulated contact-spring against which the sector A bears when the 15 instrument is unset, as shown. K is a second contact-spring which bears on the periphery of the sector when the sector is turned ahead, but is placed slightly ahead, so that when the clockwork is unwinding the sector 20 will break contact with the spring K a short time before making contact with the spring I in order that the last signal transmitted by this instrument may be distinguished from the first transmitted by the next. The line-circuit 25 enters the instrument through the transmitting-spring H, thence leads through the disk B, through the frame of the instrument, to the metal sector A. If this instrument be unset, the sector connects with the contact-spring I, from which the circuit leads 30 directly to the next call-box, which it enters in precisely the same way as in the box D', and consequently the circuit leads through all the unset boxes in series. If the instrument 35 has been set, the sector A will be in contact with the spring K and the circuit will lead through the electromagnet C to the ground, as shown, in which condition the instrument is ready to be tripped at the will of the receiving operator by his sending over the 40 circuit a current of sufficient strength to operate the electromagnet and cause the box to send its signal. By this arrangement whenever several boxes happen to be set at about 45 the same time the operator at the central office, where the signals are received, is enabled to release them and receive their signals one after the other, thus avoiding the confusion which now results from two or more subscribers 50 setting their instruments at once. The effect of setting each box is to cut off all those beyond, so that the current sent over the line by the central operator when he is prepared to receive signals will only trip the nearest 55 instrument set, and when this instrument has ceased sending its signal it automatically cuts in the next instrument, (after a short inter-

val, in which the circuit remains broken,) thus tripping the next instrument, and so on until they (all the boxes) have sent in their signals. 70 I have shown my invention as applied to a closed-circuit system, such as is commonly employed, in which a battery is kept constantly in circuit. If this battery be strong enough to trip the escapements, the instruments will 75 evidently not remain set. To prevent their being tripped when set and still make their signals recognizable, even without a recording-register in circuit, I provide at the receiving-station the circuit-breaking instrument 80 R', through which the circuit leads, which is so constructed that when the circuit is momentarily broken at one of the call-boxes (as it is while the metal sector A is passing from contact-spring I to contact-spring K in setting the hand) its armature tilts by its own 85 gravity and breaks the main circuit, as clearly shown, at the same time closing a local circuit and ringing a bell b to inform the operator there that a box has been set. Thus the 90 mere act of setting any box permanently breaks the circuit at the central office and prevents the box from being tripped. The central operator, being prepared to receive the signal or signals, depresses the key k, 95 which again closes the circuit through the releasing-battery and a sounder or receiving instrument f, upon which the signals are received in any desired manner. To enable the instrument R' to be used as an ordinary 100 sounder, if desired, I have shown it provided with a movable stop carrying hook r, which may be rocked into position to limit the play of the armature-lever. The metal sector A serves two purposes—one to connect the instrument with the spring I or with the spring 105 K and the other to hold the lever e and finger F out of engagement with the escapement G, so that the instrument will continue unwinding and the escapement not be stopped 110 by the dropping back of the electromagnet's armature during the breaks which make up the signals; but it is necessary that the finger should drop in and lock the escapement when the instrument is set, and for this purpose a notch a is cut in the sector so as to come under and allow the elbow e to drop into it and lock the escapement. A second notch a' is also cut in the sector, the object of which is as follows: Suppose a box has 115 been set and tripped and has just commenced sending its signal, and suppose a second box nearer the receiving-station to be then set. This will cut off the first box in the act of sending its signal, and the person who is 120 sending the signal will have no means of knowing that the signal of his box has been interrupted. As the instrument unwinds further, however, the notch a' comes under the elbow e, which stops the escapement before the hand has quite run down, thus indicating the fact that the instrument is stopped 125 partly run down—that its signal has been interrupted by the setting of another instru-

ment between it and the receiving-station. If the circuit had not been interrupted by the setting of a second instrument, the elbow *e* would have been held out of the notch *a'* by the electromagnet *C*, and consequently the instrument would have completely run down. To enable the instrument to be unset by the person setting it in case of mistake, I provide a button *Y*, by which the lever *E* may be disengaged from the escapement. The armature of the electromagnet also has attached to it a clapper, which strikes upon a bell, as shown by the dotted line, the object of which is to ring if during the transmission of a signal a box further along the line has been set, thus interfering with the signal being sent.

In Fig. 5 I have shown a modified apparatus, by means of which several distinct sets of signals can be transmitted when the instrument is released. Each pair of hands shown corresponds to mechanism such as hereinbefore described, and the method by which when the first set of signals has been properly released it sets off the next is the same as that already described. This is in effect simply a modification of the apparatus already shown, in which the different instruments are at separate stations or offices.

In the duplex instrument shown in Fig. 1 and the triplex instrument shown in Fig. 5 the circuit connections for each component mechanism of the whole are precisely like those in the individual instrument shown, and the connections between any two are the same, whether they are in one box at one station or are situated at different stations.

In Fig. 6, *A B C* represent the break-wheels, respectively, of three instruments to be placed at different stations on the same circuit. They enable the receiving-operator to distinguish from which one of several stations the signal is sent. It will readily be seen that although the number of teeth on each side of the wide teeth can be set so as to give the desired variable signal, as described in my previous patent, the signals transmitted by the breaks between these wide teeth is always the same, being arbitrarily fixed for each station. *B' B''* show a modification of these break-wheels, which is applicable to certain conditions in which the signal shall be composed of the makes instead of the breaks in the circuit—as, for instance, if the signal is released from an alternating-current magneto-machine—*B''* showing the blanks filled with some insulating material.

In Fig. 3 I have shown an improved form of tripping or releasing apparatus which I have devised as a substitute for that described in my previous patent referred to. Instead of having the electromagnet lock the clockwork by engaging with the escapement-wheel, as described in that patent, I construct its armature so that it engages with the vibrating pendulum, and thereby locks the escapement, so as to prevent its vibrating, and a further improvement consists in the mech-

anism by which the escapement is prevented from being locked at each break of the circuit when the instrument is transmitting its signal after the release thereof. This is accomplished by means of the pivoted lever *l*, which serves as a catch to hold the armature out of the way of the escapement while the clockwork is unwound. To enable the instrument to be set, an arm *c* is screwed to the spindle *L* in such a position with respect to the hand that when the instrument is being set by the revolution of the hand it kicks the lever *l* out of the way, and so allows the armature to drop and lock the escapement, as clearly shown in the drawings. When the current engages the electromagnet *C* and its armature is attached, this armature is caught and held up by the catch upon the lever, which drops into position.

It will readily be seen that it is not at all times necessary, indeed is in some cases not even desirable, though usually advantageous for the operation of my invention under varying conditions, that the local grounding and the cutting off of the instruments beyond the one set should be effected automatically by the act of setting them. It is enough to keep the apparatus within the scope of my invention if this is done independently when preferable, provided that the instrument automatically returns to its normal position, and thus makes possible the release of any other instrument that may be set beyond.

By the term "single line" I mean a system in which three or more boxes or stations co-operate in series with a central station by way of connections which comprise between two stations only one wire and a return, whether that be by way of ground or of another wire, thus excluding, for instance, systems having in addition to a return-wire or metallic connection also a ground connection or return. By the term "cut-off" I mean a disabling device, which acts to cut off or disable electrically the circuit connection normally existing between a box at which such cut-off is located and a box next beyond—that is, farther distant from the receiving-station. By the term "non-interference" I mean a provision or result by which when several boxes are in a condition ready to operate or are set within the same time limit the operation of neither will be able to prevent the proper reception of the signals from the other.

What I claim as my invention, and desire to secure by Letters Patent, is—

1. A series of transmitters, included in and co-operating with only a single main line leading to the stations on each side, each transmitter comprising a break-wheel and brush and motor device, and a setting device for the same; a magnet, an armature and adjuncts arranged and adapted to control the motor device, and thus to control the production of the signal by the break-wheel, together with a cut-off switch co-operating with the said line at a point between the break-wheel of the

transmitter and the break-wheel of the next more distant transmitter, and arranged to cut the latter off from the receiving-station.

2. A series of transmitters, included in and coöperating with only a single main line leading to the stations on each side, each transmitter comprising a break-wheel and brush and motor device, and a setting device for the same; a magnet, an armature and adjuncts arranged and adapted to control the motor device, and thus to control the production of the signal by the break-wheel, together with a circuit-completing switch, including elements for controlling the said main line at the box.

3. A series of transmitters, included in and coöperating with only a single main line leading to the stations on each side, each transmitter comprising a break-wheel and brush and motor device, and a setting device for the same; a magnet, an armature and adjuncts arranged and adapted to control the motor device, and thus to control the production of the signal by the break-wheel; a cut-off switch coöperating with the said line at a point between the break-wheel of the transmitter and the break-wheel of the next more distant transmitter, and arranged to cut the latter off from the receiving-station, together with a circuit-completing switch, including elements for controlling the said main line at the box.

4. A series of transmitters included in and coöperating with only a single main line leading to the stations on each side, each transmitter comprising a break-wheel and brush, a motor device and a setting device for the same; a magnet, an armature and adjuncts arranged and adapted to control the motor device and thus to control the production of the signal by the break-wheel, together with a restoring device and means for operating the same through the said single circuit to the receiving-station for restoring the normal circuit at a box after its operation.

45 5. A series of transmitters included in and coöperating with only a single main line leading to the stations on each side, each transmitter comprising a break-wheel and brush, a motor device and a setting device for the same; a magnet, an armature and adjuncts arranged and adapted to control the motor device and thus to control the production of the signal by the break-wheel; together with a circuit-completing switch including elements for controlling the said main line at the box, and a restoring device and means for operating the same through the said single circuit to the receiving-station, for restoring the normal circuit at a box after its operation.

60 6. Several transmitters, included in a single main line, each comprising a setting device, controlling-magnet and signal-transmitting elements, arranged to transmit an invariable or characteristic signal, together with a variable signal; a branch line, including

the magnet; and a cut-off operated by the act of setting the transmitter and operating to disable the line beyond; and a restoring device operating to restore the disabled line to its normal condition and controlled by the magnet.

7. Several transmitters included in the single main line, each comprising a setting device, a controlling-magnet and transmitting mechanism, including elements arranged to transmit an invariable or characteristic signal, and a variable signal; a branch line including the magnet; and a cut-off for the said main line beyond, and devices operating to simultaneously connect the branch line to the main line, and to operate the cut-off, together with a circuit-restoring device controlled by the magnet.

8. A system of four or more stations in series; receiving apparatus at one of these, and signal-boxes at the others, comprising first, signal-transmitting elements, including a setting device and break-wheel, a brush, a motor and a magnet; second, elements including contacts arranged and adapted to temporarily cut off or postpone the release of motors located in boxes which have been set farther along the line; third, internal connection-contacts arranged to control the operation of its own motor, in correspondence with the condition of its own setting device; fourth, non-interference elements, including contacts arranged—while a box which is set and so postponed is ready to be released—to operate to so cut off or postpone all operated boxes beyond; fifth, circuit connections including in addition to only one return, only one wire from any box in the direction of the receiving-station; all coöperating so that while one box is transmitting all boxes beyond will be postponed, and so that each of such postponed boxes must be separately released in succession—whereby the signals of all boxes will be duly received in succession.

9. A system comprising four or more stations coöperating with a single main line, one of these including receiving apparatus and three or more each including a signal-transmitting movement; a magnet in a branch line arranged to coöperate with the main line, and controlling means for holding or locking the movement; a cut-off for that portion of the main line extending to stations beyond; and mechanism for restoring the normal condition of the cut-off after the operation of the signal-transmitting movement; whereby the several movements are separately locked and successively released so as to transmit the respective signals in sequence and without interference.

10. A signal-transmitting box comprising a characteristic break-wheel, and a movement adapted when wound to actuate the same, and a detent for the movement; a single main line coöperating therewith and including on one side a cut-off switch; a manual setting de-

vice operating both to set the wheel and to operate the cut-off switch; a magnet in a temporary branch return, arranged to control the detent for the movement; and means where-
5 by the operation of the movement breaks the connection of the main line to the said branch and recloses the main line at the said cut-off.

In testimony whereof I have signed my name to this specification in the presence of two subscribing witnesses.

F. BENEDICT HERZOG.
